THERMOCHROMIC THERMOMETER

Philip L. Van Kersen, P.O. Box 40423,
Indianapolis, Ind. 46240

Filed Apr. 28, 1975, Ser. No. 572,308

Term of patent 14 years

Int. Cl. D10—04

U.S. Cl. D10—57

Fig. 1

Fig. 2

Fig. 3

FIG. 1 is a front elevational view of a thermochromic thermometer showing my new design;

FIG. 2 is a rear elevational view thereof; and

FIG. 3 is a side elevational view thereof, the other sides not shown being identical thereto.

I claim:

The ornamental design for a thermochromic thermometer, as shown and described.
